UNITED STATES PATENT OFFICE.

JAMES S. GLEDHILL AND WILLIAM H. SMITH, OF LOS ANGELES, CALIFORNIA.

DESIGN FOR AN ANIMAL FIGURE.

59,470.

Specification for Design.

Patented Oct. 25, 1921.

Application filed March 15, 1921. Serial No. 452,549. Term of patent 7 years.

To all whom it may concern:

Be it known that we, JAMES S. GLEDHILL and WILLIAM H. SMITH, both citizens of the United States, residing at Los Angeles, in the county of Los Angeles and State of California, have invented a new, original, and ornamental Design for Animal Figures, of which the following is a specification, reference being had to the accompanying drawing, forming a part thereof.

Figure 1 is a front elevation of an animal figure showing our new design, and Fig. 2 is a side elevation thereof.

We claim:

The ornamental design for an animal figure, as shown.

J. S. GLEDHILL.
WM. H. SMITH.
